US00D910959S

(12) **United States Design Patent** (10) **Patent No.:** **US D910,959 S**
Layne (45) **Date of Patent:** **** Feb. 16, 2021**

(54) **CONVEYOR GUIDERAIL**(71) Applicant: **SPAN TECH LLC**, Glasgow, KY (US)(72) Inventor: **James L. Layne**, Bowling Green, KY (US)(73) Assignee: **SPAN TECH LLC**, Glasgow, KY (US)(***) Term: **15 Years**(21) Appl. No.: **29/659,785**(22) Filed: **Aug. 13, 2018****Related U.S. Application Data**

(63) Continuation of application No. PCT/US2018/033665, filed on May 21, 2018.

(51) **LOC (13) Cl. 12-05**(52) **U.S. Cl. USPC .....** **D34/29; D34/35**(58) **Field of Classification Search**

Primary Examiner — Cynthia Ramirez(74) *Attorney, Agent, or Firm* — King & Schickli, PLLC(57) **CLAIM**The ornamental design for a conveyor guiderail, as shown
and described.**DESCRIPTION**FIG. 1 is a perspective view of a conveyor guiderail showing
my new design;FIG. 2 is a front view of the curved guiderail of FIG. 1;
FIG. 3 is a right view of the curved guiderail of FIG. 1;
FIG. 4 is a rear view of the curved guiderail of FIG. 1;
FIG. 5 is a front view of the curved guiderail of FIG. 1;
FIG. 6 is bottom view of the curved guiderail of FIG. 1; and,
FIG. 7 is a top view of the curved guiderail of FIG. 1.
The conveyor guiderail is shown with a symbolic in its
length. The appearance of any portion of the article between
the break lines forms no part of the claimed design.
The broken line depictions illustrate the environment of use,
and form no part of the claimed design.**1 Claim, 2 Drawing Sheets**US D910,959 S
